RADIORECEIVER

Hal Craig, Hollywood, Calif.

Application July 19, 1930. Serial No. 469,212

9 Claims. (Cl. 250—14)

This invention relates to a radio receiver and in particular to a radio receiver constructed for use on an automobile or other vehicles.

The mounting of radio receivers on automobiles presents numerous problems that demand no solution in radio receivers constructed for domestic use. Economy of room in the domestic receiver may be desirable at times although not essential. In a radio receiver for automobile use it is essential to reduce the space occupied by the radio receiver to a minimum. It is also desirable to eliminate shielding as far as possible consistent with the performance of the device.

An object of this invention is to arrange the parts with the minimum amount of shielding. This has been accomplished by staggering the transformers of the radio frequency stages with respect to the gang condensers arranged in a row so that the input transformer to a tube is on the opposite side of the gang condensers from that of the output transformer. It can be readily seen that by so arranging the transformers undesirable coupling is greatly diminished. This is especially the case when the transformers are all arranged in a common plane. This permits the close assembly of the radio and audio frequency stages of amplification within the same metallic case without coupling even though the several stages are unshielded.

Another object of this invention is to decrease the length of the leads so as to eliminate disturbances caused by long leads. This has been accomplished by arranging the gang condenser or tuning condenser intermediate the input transformer and the tube so that the tuning condenser forms a portion of the lead coupling the secondary winding of the input transformer to the control electrode or grid. By this arrangement the lead extending from the plate to the primary winding of the output transformer may be reduced.

Another object of this invention is to get a compact assembly. This has been accomplished by staggering the radio frequency stages so as to thereby better group the parts, thus reducing the space occupied by these.

Further objects and advantages of the present invention will be apparent from the following description, reference being had to the accompanying drawings, wherein a preferred embodiment of one form of the present invention is clearly shown.

In the drawings:

Fig. 1 discloses a schematic arrangement of the parts of the radio receiver.

Fig. 2 discloses a schematic wiring diagram of the complete radio receiver.

Fig. 3 discloses a sectional view of the receiver taken on the line 3—3 of Fig. 1.

In the drawings the reference characters 10, 12, 14 and 16 represent the stators of gang condensers provided with the rotors 18, 20, 22 and 24 arranged on a common shaft 25 so that the condensers may be adjusted in unison to the same resonant frequency.

The radio frequency transformers 26, 28, 30 and 32 have been staggered with respect to the shield 34 shown in dashed lines in Fig. 1, enclosing the gang condensers so as to reduce the undesirable coupling that is generally found in conventional type radio receivers where the transformers are not enclosed in shields. In addition to being staggered the axes of the radio frequency transformers have been arranged in a plane thereby reducing the electromagnetic coupling. This plane defined by the axes of the radio frequency transformers is parallel to the shaft upon which the rotors are mounted and passes through the stators of the condensers so as to intersect all of the stators into like sectors as best seen in Fig. 3.

The radio frequency amplifying tubes 36, 38 and 40 together with the detector tube 42 have also been staggered with respect to the gang condensers and the shield 34 so that these tubes are arranged opposite to their respective input transformer and adjacent to their respective output transformer.

The signal from the detector 42 is amplified by means of the audio frequency amplifier that includes the audio transformer 44 and the tube 46. The output from the tube 46 is amplified by the tubes 48 and 50 having their grids 52 and 54 arranged in parallel and the plates 56 and 58 also arranged in parallel. The details of the electrical circuit have not been described for the reason that this forms no part of this invention.

When this radio receiver is mounted within a metallic casing such as either copper or aluminum, the ends of the coils 26, 28, 30 and 32 may be shielded by the shields 60, 62, 64 and 66, indicated in Fig. 1 by dashed lines, that may be cup-shaped which probably prevents undesirable coupling intermediate the enclosing shield 68 and the radio frequency transformers.

While the form of embodiment of the present invention as herein described, constitutes a preferred form, it is to be understood that other forms might be adopted, all coming within the scope of the claims which follow.

What is claimed is as follows:

1. A multi-stage radio receiver including gang condensers arranged in a row, a shield enclosing said gang condensers, and radio frequency transformers of adjacent stages arranged in a staggered relation with respect to and on alternate sides of the shield so as to reduce the undesirable coupling between the transformers thereby reducing undesirable oscillations in the radio receiver. 80
- 10 2. A multi-stage radio receiver including a plurality of gang condensers arranged in a row, a shield for shielding the condensers and transformers of adjacent stages arranged in stepped relation on opposite sides of the gang condensers, vacuum tubes arranged on opposite sides of said condensers and directly opposite said transformers so as to eliminate undesirable coupling between adjacent transformers thereby reducing 85 undesirable noises in the radio receiver. 90
- 15 3. A multi-stage radio receiver including a plurality of gang condensers aligned in a row, a common shaft for the rotor of said condensers so as to rotate the rotors in unison, and transformers of adjacent stages arranged on opposite sides of the gang condensers and alternating with their respective tubes, said transformers being spaced substantially equidistant so as to eliminate undesirable coupling causing undesirable noises in 95 said radio receiver, and compactly arranged so as to shorten the connecting leads. 100
- 20 4. A radio receiver including gang condensers arranged in a row, transformers arranged on opposite sides of said gang condensers, and vacuum tubes arranged opposite each transformer so that the gang or tuning condenser is intermediate the input transformer and its tube, an element of the condenser forming part of the electrical connection intermediate the secondary of 105 an input transformer and the grid of the succeeding tube. 110
- 25 5. A radio receiver including a plurality of gang or tuning condensers aligned in a row, radio frequency transformers placed on opposite sides of said gang condensers in a staggered relation, thermionic vacuum tubes arranged on opposite sides of the condensers so that the tubes are arranged in a staggered relation, the primary coil of the output transformer having its winding connected to the plate circuit of a vacuum tube that is adjacent to and on the same side of the gang condensers as said output transformer thereby reducing the length of the leads so as to decrease undesirable noises in the radio receiver. 115
- 30 6. In a radio receiver having a plurality of successive stages of radio frequency including a tube, a condenser and transformer in each stage, the combination comprising, a tube and its respective transformer being arranged on opposite sides of 120
- 35 7. In a compact radio receiver characterized by a plurality of stages of radio frequency, in which each stage includes a tube, condenser and a transformer, the combination comprising, means for grouping and operating the condenser as a gang, said tube and transformer of each stage being arranged on opposite sides of its respective transformer, and the tubes and transformers of each stage alternating respectively with the tubes and transformers of adjacent stages so that the tubes and the transformers are arranged in staggered relation on both sides of the condenser gang, the staggered relation of the tubes and transformers providing for short and uniform 125 grid and plate leads. 130
- 40 8. A radio receiver having a compact arrangement of parts, comprising in combination, a plurality of stages of audio frequency including a transformer, condenser and a vacuum tube in each stage, said condensers being aligned in a row, said transformer and tube of each stage being positioned on opposite sides of and closely related to their respective condenser, and transformers and tubes of the successive stages being arranged on alternate sides of the line of condensers to form a stepped relation of both transformers and tubes as respects the condenser line, said transformers being disposed adjacent tube or tubes of adjacent stages and at the base thereof to provide for a closer grouping of the said tubes, said compact arrangement of transformers, condensers and tubes providing for short leads between the elements of the receiver. 135
- 45 9. A radio receiver having a compact arrangement of parts, comprising in combination, a plurality of stages of radio frequency including a transformer, condenser and a vacuum tube, each transformer and tube being arranged on opposite sides of the condenser in each stage, and each alternately arranged on opposite sides of the condenser line for succeeding stages, each tube being positioned opposite to its respective input transformer and adjacent to its respective output transformer, such compact arrangement of transformer, condenser and tube elements providing for the use of short and uniform leads, and the alternate arrangement of the transformers eliminating undesirable coupling between successive stages. 140
